UNITED STATES PATENT OFFICE.

LUCRETIA V. PIERCE, OF ST. LOUIS, MISSOURI.

COMBINED STOVE, TABLE, AND CABINET.

SPECIFICATION forming part of Letters Patent No. 279,276, dated June 12, 1883.

Application filed February 23, 1883. (No model.)

To all whom it may concern:

Be it known that I, LUCRETIA V. PIERCE, of St. Louis, Missouri, have made a new and useful Combined Stove, Table, and Cabinet, 5 of which the following is a full, clear, and exact description, reference being had to the annexed drawings, making part of this specification, in which—

Figure 1 is a plan of the improvement; Fig. 10, 2, a side elevation; Fig. 3, a plan, the top being swung around to expose and provide access to the stove and cabinet; Fig. 4, a side elevation of the construction as when the top is swung around; Fig. 5, a detail, being an 15 edge elevation of the upper portion of the leg used in supporting the top when opened out; and Fig. 6, a detail, being a horizontal section on the line 6 6 of Fig. 2.

The same letters of reference denote the 20 same parts.

The present improvement consists, substantially, of an oil or gas stove surrounded by a series of receptacles for articles of food or for use in cooking, and a top which can be closed 25 over the stove and receptacles, and when thus closed serving to convert the construction into a table.

A represents the combined stove, table, and cabinet.

30 B represents a vapor-burner or any form of oil or gas stove.

C C C represent a series of receptacles arranged around the burner. Any desired number of receptacles can be used and of any suitable shapes. They are intended for holding 35 any of the various less bulky articles of food, or articles used in preparing food, such as flour,

spices, knives, and forks. The receptacles and stove are supported upon a base, D, which may be of suitable form for upholding the superstructure, but which is preferably made, as shown, of the legs d d d, spaced apart in the vicinity of the burner and united at d', the part uniting the legs being in the form of a receptacle, the cover d' of which is shown 45 raised in Fig. 2.

E represents the top, which is shown closed in Figs. 1, 2 and opened in Figs. 3, 4, the top at e being pivoted to its support and being adapted to be swung around to and from 50 the two positions described. The top is provided with a leg, F, which aids in supporting the top when opened out, as in Figs. 3, 4, and which, when the top is closed, as in Figs. 1, 2, folds compactly against one of the legs d d. 55 The leg F in shape conforms to the leg d, against which it folds, and when closed against the leg d it can be secured by means of a catch, G. The leg F has an offset at f to enable the leg to fit and fold beneath the receptacles C; 60 and to enable the leg to better support the top when opened out, it is provided with a brace, f', which, when the top is opened, can be turned up, as shown in Figs. 4, 5, against the under side of the top.

I claim—

The combination of the stove B, the receptacles C C C, the base D, the swinging top E, the leg F, attached to said top, and the clamp G, substantially as described.

LUCRETIA V. PIERCE.
